UNITED STATES PATENT OFFICE.

PETER S. KINSEY, OF NEWARK, ASSIGNOR TO THE AUSTRALIAN KNITTING COMPANY, OF PATERSON, NEW JERSEY.

DESIGN FOR A KNITTED FABRIC.

SPECIFICATION forming part of Design No. 19,098, dated May 14, 1889.

Application filed April 12, 1889. Serial No. 307,034. Term of patent 7 years.

To all whom it may concern:

Be it known that I, PETER S. KINSEY, of Newark, in the county of Essex and State of New Jersey, have invented and produced a new and original Design for Knitted Fabrics, of which the following is a specification.

The accompanying drawing illustrates a design embodying my invention, the design being shown in the white portions of the figure.

The design consists, essentially, of a zigzag figure, A, near one edge of the design, sepa-

rate substantially rectangular figures B near the other edge, and a substantially-straight line, C, intermediate of the figures A B.

What I claim as my design is—

The design for knitted fabrics, substantially as herein shown and set forth.

PETER S. KINSEY.
